WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

AUTOMATIC TRAIN-CONTROL SYSTEM.

Application filed February 5, 1915, Serial No. 6,248. Renewed October 2, 1920; Serial No. 414,337.

To all whom it may concern:

Be it known that I, WINTHROP K. HOWE, a citizen of the United States, and a resident of the city of Rochester, in the county of

5 Monroe and State of New York, have invented new and useful Improvements in Automatic Train-Control Systems, of which the following is a specification.

This invention relates to an automatic 10 train control system.

The primary object of this invention is a construction and arrangement whereby the movement of a movable vehicle on a trackway may be controlled by means other than 15 by an application of the well known emergency brake and also in addition by an application of the well known emergency brake or an apparatus having similar effects upon the train.

20 Other objects and advantages will appear as the description of the invention progresses, and the novel features of the invention will be particularly pointed out in the appended claims.

25 In describing the invention in detail reference is had to the accompanying drawing, comprising a single figure, which is a schematic illustration of a railway track with a car thereon, equipped with train-controlling 30 mechanism.

1 and 2 designate the two rails of a railway track, one of which is shown as divided into sections by means of the well known insulating joints 3. At points close to the insulating joints sources of current, as 4 and 5, are connected across the rails of the trackway, and on the other side of the insulating joints are connected translating devices, as 6, 7 and 8. The dividing of one rail of the track by insulating joints and connecting a source of current across the rails of one point between two joints and a relay at another point between the same two joints, forms the well known track circuit section, so that the railway is thereby divided into closed circuited track circuit sections, which are perfectly familiar to and thoroughly understood by those skilled in the art of railway signalling. The sources of current are herein shown as the secondaries of transformers, of which the primaries are 9 and 10, which are connected across the two line

wires, 12 and 11, which extend the length of the trackway and which are connected at some point to a generator of alternating current 13.

Opposite each insulating joint is placed a ramp, as 14, 15 and 16, the greater portion of the ramp being in advance of the insulating joints in the direction of traffic, which is 60 in the direction of the arrow A, for a purpose to be hereinafter more fully explained.

At or about the location of each ramp is positioned a transformer, of which the primaries are designated by 17, 18 and 19, 65 which are each connected across the line wires 12 and 11. Each of the primaries 17, 18 and 19 has a secondary formed in three parts; that is, the primary 17 has the secondary, formed of the three parts, 20, 21 and 70 22; the primary 18 has a secondary formed of the three parts, 23, 24 and 25; and the primary 19 has a secondary formed of the three parts, 26, 27 and 28. One terminal of each of the secondaries 20, 23 and 26 is connected directly to the track rail 1 by the wires 29, 30 and 31 respectively. The other terminal of the secondaries, 20, 23 and 26, are connected by means of the wires 32, 33, 75 and 34, respectively, to the back contacts of the armatures 35, 36 and 37, respectively, of the relays 6, 7 and 8, respectively. One terminal of the secondary portions 21, 24 and 27 is connected to one terminal of the secondary portions 20, 23 and 26, respectively, and the 80 other terminal of the secondary portions 21, 24 and 27 is connected by means of wires 38, 39 and 40 respectively to front points in operative relation with the armatures 35, 36 and 37, respectively, of the relays 6, 7 and 8, 85 respectively. One terminal of the secondary portions 22, 25 and 28 is connected to one terminal of the secondary portions 21, 24 and 27, respectively, and the other terminal of the secondary portions 22, 25 and 28 is 90 connected by means of the wires 41, 42, and 43, respectively, to front points in operative relation with the armatures 44, 45 and 46, respectively, of the relays 6, 7 and 8, respectively.

100 Current which may reach a ramp, as 14, 15 or 16, is caused to flow through circuit controllers 47, 48 and 49 respectively, which are normally in the closed position, but may

be opened by any desired or appropriate means to produce an effect hereinafter more fully described.

A movable vehicle has been herein illustrated as consisting of the wheels 50 and 51 connected by the axle 52, which supports the journal box 53 bearing the side bar 54 which for simplicity is assumed to be made of a suitable insulating material. The side bar 54 has a projection 55 by which is supported a shoe 56, which is freely movable vertically in the projection 55, and is caused to move downwardly by reason of the collar 57 rigidly attached to the shoe 56 by means of the spring 58, which is positioned between the collar 57 and the projection 55, but the shoe 56 is prevented from moving too far downwardly by reason of the enlarged upper end 59 which comes in contact with the projection 55 and prevents too great a downward movement of the shoe 56.

The side bar 54 also supports three circuit controllers, one of which is composed of the movable pivoted part 60 and the fixed part 61; another of which is composed of the part 62, similar to the part 60; and the part 63, similar to the part 61; the third of which is composed of the part 64, similar to the part 60, and the part 65, similar to the part 61. When the shoe 56 is at the downward limit of its movement the parts 60, 62 and 64 are moved by gravity, or any appropriate means, into contact with the fixed parts 61, 63 and 65 respectively, but when the shoe 56 is raised by contact with a ramp, as 14, then the parts, 60, 62 and 64 each break contact with the parts, 61, 63 and 65, respectively.

Each movable vehicle is equipped with a relay 66, a relay 67 having two windings thereon, 67¹ and 67², a relay 68, a relay 69, a means for controlling the movement of the vehicle other than by an emergency application of the brakes, 70, and a means, 71, for controlling the movement of the vehicle by an application of the emergency brake, or similar apparatus.

It is to be understood that emergency brake controlling means 71 may be of any of the well known forms which vent a train line upon deenergization and will not stop venting the train line even if reenergized until the air pressure in the train line has been reduced to a certain value.

Operation.—Normally, when the vehicle or train is traveling in a track section or block between the ramps at the entrance to said blocks and has not approached any train immediately ahead, the relays 67 and 69 are energized, while the relays 66 and 68 are deenergized. The circuit for maintaining the relay 67 normally energized while the train is traveling between ramps under safe proceed conditions, may be traced as follows: one terminal of the battery 81, wires 82 and 90, member 63, member 62, wire

91, armature 87, wire 92, coil 67² and wires 93 and 86 to the other terminal of the battery 81.

When the relay 67 is energized and its armature 89 is in the upper position, the train controlling mechanism is energized by a circuit which may be readily traced on the drawing so that this controlling mechanism will have no effect upon the movement of the vehicle, other than to impose such limitations on its speed or its movement in other respects as may be found expedient even when the vehicle is traveling under safe proceed conditions, all depending upon the particular character and functions of the mechanism 70.

The circuit for normally energizing the relay 69 when the vehicle is traveling between ramps may be traced as follows: one terminal of the battery 111, wire 112, member 60, member 61, wire 113, relay 69, wire 114 armature 98 and wire 115 to the other terminal of the battery 111.

Current flowing in the above traced circuit which maintains the relay 69 energized and its armature 99 in the upper position, as shown, completes a circuit for energizing the emergency brake controlling apparatus 71 which may be traced as follows: one terminal of the source of current 100, wires 101 and 102, armature 99, wires 103 and 104, emergency brake controlling apparatus 71 and wire 105 to the other terminal of the battery 100. The energization of the emergency brake controlling apparatus will prevent that apparatus from having any effect upon the movement of the vehicle.

The parts on the vehicle are caused to assume the normal position, hereinbefore described, when the vehicle passes a ramp energized with high voltage, as will be explained more fully hereinafter, and in practicing the invention, it is contemplated that such an energized ramp will be located at the point where the vehicle commences its trip. In order to make the operation and function of the various parts and circuits more clearly understood, different traffic conditions will be assumed and the operation and circuits established under these different traffic conditions will be pointed out in detail.

For the first traffic condition, assume that the vehicle in question has been proceeding along the track without coming into immediate proximity to another vehicle ahead, and has reached the point, as shown in the drawing, where its contact shoe 56 is in contact with the ramp 14, although the first pair of wheels and axle of the vehicle has not yet passed over the insulating joint 3 into the block or track section to which the track relay 6 is connected, it being further assumed that no other train occupies either of the next two blocks in advance.

Assuming the conditions just described, when the contact shoe 56 is in contact with the ramp 14, a circuit will be formed as follows: One terminal of the secondary portion 22, wire 41, armature 44, wire 72, circuit controller 47 in the closed position, wire 73, ramp 14, shoe 56, wires 74 and 75, impedance 76, wire 77, relay 66, wires 78 and 79, journal box 53, axle 52, wheel 50, rail 1, wire 29, secondary portion 20 and secondary portion 21 to the other terminal of secondary portion 22. The high difference of potential created by including all of the secondary portions 20, 21 and 22 in series in the above traced circuit will cause such a flow of current through the relay 66 even with the impedance 76 in series therewith as will cause it to become sufficiently energized to raise its armatures, as 80 and 117. The raising of armature 80 to the upper position, as shown, will cause a flow of current through one coil 67¹ of the relay 67 in a circuit as follows: One terminal of the battery 81, wires 82 and 83, armature 80, wire 84, coil 67¹ and wires 85 and 86 to the other terminal of the battery 81. Current flowing in the above traced path will sufficiently energize the relay 67 as to cause it to maintain in the upper position each of its armatures 87, 88 and 89. The armature 89 being in its upper position will maintain energized the train controlling mechanism 70 so that it will have no effect upon the movement of the vehicle.

The armature 87 being held in its upper position will complete the stick circuit hereinbefore traced for the relay 67 in which current will flow, as soon as the shoe 56 passes so far down the inclined portion of the ramp 14 as to allow its upper end 59 to descend such a distance as will allow the movable members 60, 62 and 64 to make contact with the fixed portions 61, 63 and 65 respectively.

The contact of shoe 56 with ramp 14 will also cause current to flow at the same time as it commences to flow through relay 66 in a circuit as follows: One terminal of the secondary portion 22, wire 41, armature 44, wire 72, circuit controller 47 in the closed position, wire 73, ramp 14, shoe 56, wires 74, 75, 94 and 116, armature 117, in its lower position, wires 118 and 96, relay 68, wires 97 and 79, journal box 53, axle 52, wheel 50, wire 29, secondary portion 20 and secondary portion 21 to the other terminal of the secondary portion 22. Current flowing in the above traced path will sufficiently energize relay 68 to maintain its armatures 98 and 99 raised to the upper position, as shown.

The armature 99 being in the upper position, as shown, will complete the circuit hereinbefore traced for energizing the emergency brake controlling apparatus 71.

The emergency brake controlling apparatus 71 is not only energized by the circuit hereinbefore traced, but is also energized by

a circuit which is closed only while the shoe 56 is in or near its lower position; that is, when it is in such a position that the circuit controllers controlled thereby are in the closed position, which circuit is as follows: One terminal of the battery 100, wires 101 and 106, member 64, member 65, wires 107 and 104, emergency brake controlling apparatus 71 and wire 105 to the other terminal of the battery 100. Current flowing in the above traced path maintains the energization of the emergency brake controlling apparatus 71 at all times when the shoe 56 is in a position such that the circuit controllers controlled thereby are in the closed position. It follows therefore that until the shoe 56 contacts with a ramp as 14 the energization of the emergency brake controlling apparatus 71 is maintained. When the shoe 56 contacts with an energized ramp as 14, the relay 68 is energized; so that, although the circuit through the members 64 and 65 for the emergency brake controlling apparatus is broken, the other circuit for energizing this apparatus which is controlled by the armature 99 is closed, since the armature 99 is held in its upper position by the energization of the relay 68, so that if shoe 56 contacts an energized ramp no action of the emergency brake controlling apparatus 71 will take place.

As the vehicle progresses and its first pair of wheels and axle enter upon the track circuit section to which the relay 6 is connected, that relay will be deenergized and its armatures 44 and 35 will fall by gravity and make contact with the back contacts thereof, but this deenergization takes place before shoe 56 has passed off from ramp 14; in fact, the shoe 56 should at that time be somewhat back of the longitudinal center of the ramp 14 for a reason to be hereinafter more fully explained. The deenergization of relay 6 and the dropping of armature 44 does not, however, deenergize the relay 66 under the particular traffic conditions assumed, where there are no trains upon any portion of the trackway illustrated, because the dropping of armature 44 causes a contact of armature 44 with wire 108 so that then a circuit is formed as follows: One terminal of secondary portion 24, wire 39, armature 36, wire 108, armature 44 in its lower position, wire 72, circuit controller 47 in the closed position, wire 73, ramp 14, shoe 56, wires 74 and 109, armature 88, wires 110 and 77, relay 66, wires 78 and 79, journal box 53, axle 52, wheel 50, rail 1, wire 30 and secondary portion 23 to the other terminal of secondary portion 24. The circuit just traced allows the full potential of the two secondary portions, 23 and 24, to be created between the ramp 14 and the rail 1, so that the relay 66 is maintained energized and so the relay 67 is maintained energized and the

armature 89 is held in its upper position and no change in the brake controlling apparatus 70 takes place. It should also be noticed that the circuit last traced did not include 5 wire 75 and impedance 76, because due to the fact that relay 67 was energized when the circuit traced was formed, the relay armature 88 was in the upper position, as shown, and, therefore, formed a shunt 10 around the impedance 76, so that, although the number of secondary coils included in the circuit were less than when the shoe 56 first struck the ramp, nevertheless due to the fact that the impedance 76 is cut out of the 15 circuit, the voltage is sufficient to cause a sufficient flow of current through relay 66 to maintain it energized.

Not only would current flow through the relay 66 after the wheels of the vehicle had 20 passed upon the section to which the relay 6 is connected, but it would also flow through the relay 68 in a circuit as follows: One terminal of the secondary portion 24, wire 39, armature 36, wire 108, armature 44, wire 25 72, circuit controller 47 in the closed position, wire 73, ramp 14, shoe 56, wires 74, 75 and 94, impedance 95, wire 96, relay 68, wires 97 and 79, journal box 53, axle 52, wheel 50, rail 1, wire 30 and secondary portion 36 23 to the other terminal of secondary portion 24. Current flowing in the above traced path would maintain the energization of relay 68 and so maintains armature 99 in the upper position, as shown, so that 35 the emergency brake controlling apparatus 71 would be maintained energized so that there would be no effect upon the movement of the train.

The circuit of relay 68 has been hereinbefore traced as including wires 116, armature 117 and wire 118, but as soon as relay 66 is energized the armature 117 is raised to the upper position, as shown, so that all of the current which reaches relay 68 would 45 have to flow through impedance 95, thereby decreasing the flow of current in the circuit, including relay 68, so as to prevent unnecessary waste of energy and to enable relay 66 to get the greater share.

50 From the foregoing it can be seen that when the vehicle passes the ramp at the entrance to a block, under proceed traffic conditions, when neither that particular block or the next block in 55 advance is occupied by another train, the train controlling mechanism 70 is maintained in its normal ineffective condition, and the emergency brake controlling apparatus 71 is also maintained in its normal 60 ineffective condition. As the contact shoe 56 of the vehicle leaves engagement with the ramp 14, the shoe is permitted to be moved downward by the spring 58 far enough to bring the members 60, 62 and 64 into electrical contact with the members 61, 63 and 65,

before said shoe leaves electrical contact with the ramp 14, so that the maintaining or stick circuits for the relays 67 and 69 are re-established before the relays 66 and 68 become deenergized.

For the next traffic condition to be considered, assume that the vehicle in question approaches the ramp 14, moving in the direction indicated by the arrow A, while another train is upon the rails of the track 75 circuit section to which the track relay 7 is connected. When the contact shoe 56 engages with the ramp 14, the high voltage energizing circuits hereinbefore traced and explained, will be formed through the relays 66 and 68 in the same way as previously pointed out, and will act to keep the train controlling mechanism 70 and the emergency 80 brake controlling apparatus 71 energized; but before the shoe 56 leaves engagement with the ramp 14, the first pair of wheels and axle of the vehicle enters the track circuit section to which the track relay 6 is connected, thereupon causing the armature 44 of said relay 6 to move to the lower position and establish contact with the wire 108. Since the block or track section to which the track relay 7 is connected, is now assumed to be occupied by another train, the armature 36 of said track relay 7 is in its lower position, so that, with the armature 44 in contact with the wire 108, and the armature 36 in the lower position, the voltage available for causing current to flow through the relays 66 and 68 on the vehicle is merely that 90 between the terminals of the secondary portion 23, and this voltage, which is conveniently termed low voltage, is not sufficient, even with the shunt established around the impedance 76 by the armature 88, to maintain the energization of the relay 66. Consequently, while the shoe 56 is still in engagement with the ramp 14, the relay 66 is deenergized; and the relay 67 in turn will 100 also be deenergized, because its stick circuit hereinbefore traced is broken at the members 62 and 63 of the contact shoe. When the relay 67 is deenergized, its armature 87 drops and opens a break in the stick circuit for said relay 67, so that although the members 62 and 63 contact with each other when the shoe 56 leaves engagement with the ramp 14, the coil 67² is not energized. Also, when the relay 67 is deenergized, its armature 88 110 breaks the shunt around the impedance 76, for the purpose pointed out more fully hereinafter. Also, when the relay 67 is deenergized, the armature 89 thereof drops and 115 interrupts the circuit which normally energizes the train controlling mechanism 70, thereby setting this mechanism into operation and rendering it active to control the movement of the vehicle in some appropriate way as it progresses. The exact form of 120 control exerted by the mechanism 70 on the 125 130

vehicle is not material to this invention, although this mechanism is preferably of some suitable type which acts gradually to require the vehicle to reduce its speed as it progresses so as to avoid a collision with the train ahead.

The difference of potential created by the secondary portion 23 between the ramp 14 and the track rail 1, is, however, sufficient to energize the relay 68, so that its armatures 98 and 99 remain in the upper position as shown; and in this way, the emergency brake controlling apparatus 71 is not de-energized and will not, therefore, in any way control the movement of the train.

From the foregoing it can be seen that when the vehicle passes a ramp, as the ramp 14, at the entrance to the block, when the next block in advance is occupied by another train, the train controlling mechanism 70 is set into operation, while the emergency brake controlling apparatus 71 is still maintained in its normal inactive condition.

Assuming that the vehicle, after having had its train controlling mechanism 70 set into operation, as described, when it passes the ramp 14, continues through the block it has just entered, until it reaches the ramp 15; and further assume that during the time required for the vehicle to reach the ramp 15, the train formerly assumed to occupy the block to which the track relay 7 is connected, has in the meantime moved on entirely into the next block. Under this assumed condition the track relay 7 is energized, and its armature 45 is in the upper position, so that a high difference of potential, equivalent to the entire voltage of the secondary portions 23, 24 and 25, is established between the ramp 15 and the track rail 1. When the shoe 56 of the vehicle in question engages the ramp 15, the high voltage applied to this ramp causes sufficient current to flow through the relay 66, even with the impedance 76 included in series with said relay, so that the armatures of the relay 66 are raised. The raising of the armature 80 of the relay 66 energizes the coil 67¹ of the relay 67 and restores the armatures 87, 88 and 89 of said relay 67 to the upper position, thereby re-applying energy to the train controlling mechanism 70. As the vehicle in question progresses and enters the block to which the track relay 7 is connected, the train controlling mechanism 70 will be again set into operation by reason of the fact that a train occupies the next block in advance to which the track relay 8 is connected, in the same way as hereinbefore described.

Assume that the vehicle in question, after having its train controlling mechanism set into operation when it passed the ramp 14, continues its movement and reaches the ramp 15; and further assume that the train formerly assumed to occupy the block to which

the track relay 7 is connected still remains in this block. Under these conditions the track relay 7 is deenergized and its armature 45 is in the lower position, so that the voltage applied to the ramp 15 is either medium or low voltage, depending upon whether or not the block to which the relay 8 is connected is occupied. In any event, whether medium or low voltage is supplied to the ramp 15, sufficient current does not flow through the relay 66, which now, by reason of the fact that the armature 88 is in the lower position, has the impedance 76 in series therewith, to cause said relay to raise its armatures; and consequently, the train controlling mechanism 70 is maintained de-energized and continues to be effective to control the movement of the vehicle. The medium or low voltage applied to the ramp 15 is, however, sufficient to energize the relay 68 and hold the armatures 98 and 99 in their upper position in spite of the fact that the relay 69 is deenergized by the engagement of the shoe 56 with said ramp 15; and consequently, the emergency brake controlling apparatus 71 is still energized and does not act to control the movement of the vehicle.

From the foregoing it can be seen that, when the train controlling mechanism 70 on the vehicle has been set into operation due to the presence of another train immediately ahead, this mechanism will be temporarily restored to its normal inactive condition and again set into operation, providing the train ahead has moved entirely into the next block in advance of the block it formerly occupied. If the train ahead has not advanced, however, the mechanism 70 will remain in its active condition, while the emergency brake controlling apparatus 71 will not be affected in either case.

If the train having relays 66, 67 and 68 on it deenergized approached the ramp 14 moving in the direction of the arrow A and its shoe contacted with ramp 14 at a time when circuit controller 47 was opened, either manually or by any desired means, then there would be no potential difference between ramp 14 and the rail 1; consequently relay 66 would not be energized and relay 67 would not be energized, and, consequently, the brake controlling means 70 would be de-energized and would act in any desired manner to control or regulate the movement of the vehicle, but in addition the emergency brake controlling apparatus 71 would also be deenergized, that is, an absolute stop would be effected, because the contact of shoe 56 with ramp 14 would break contact between the members 64 and 65 so that the circuit hereinbefore traced, including the source of current 100, the emergency brake controlling apparatus 71, and members 64 and 65, would be broken and at the

130

same time the other circuit, including armature 99 and source 100, and the emergency brake controlling apparatus 71, would also be broken, because the movement of shoe 56 upwardly would break contact between members 60 and 61 and so break the stick circuit of relay 69, so that as relay 68 is not at that time energized the armatures 98 and 99 would fall.

10 It should be understood that the circuit of emergency brake controlling apparatus 71 would only be broken in regular practice by the total deenergization of the ramp next ahead in the direction of traffic from a ramp 15 between which and a rail a high followed by a low difference of potential exists so that the train approaching the totally deenergized ramp would be moving under the control of the deenergized train controlling mechanism 70 so that its speed would necessarily be so low that upon a deenergization of the emergency brake controlling apparatus 71 the train would be stopped before the shoe left the ramp and would remain there 25 until a difference of potential were created between the ramp and the rail.

From the above description it will be seen that if a car equipped as hereinbefore described approaches the first ramp of a portion 30 of trackway constructed and connected as hereinbefore described it may find five different conditions as regards difference of potential between the first ramp and a track rail, to wit: First, a high difference of potential followed by a medium difference of potential between the ramp and a track rail; second, a high difference of potential followed by a low difference of potential; third, a medium difference of potential; fourth, a 35 low difference of potential; fifth, no difference of potential.

When a vehicle equipped with the parts and circuits as hereinbefore described approaches a ramp with all of its relays, except 45 66 and 68, energized, then when it contacts with the ramp, if a high difference of potential, followed by a medium difference of potential, exists between the ramp and a track rail no control of the movement of the 50 train would be caused by devices 70 or 71; if a high followed by a low difference of potential, or a low difference of potential, exists between the ramp and a track rail, then the movement of the train will be controlled by device 70 only; if no difference of potential exists between the ramp and a track rail, then the movement of the train will be controlled both by device 70 and by device 71.

60 In regular operation a train would not approach a ramp, other than the first ramp and probably not that, between which and the track rail a medium difference of potential existed with relay 67 energized, because the preceding ramp in regular operation 65 would have deenergized relay 67. To illus-

trate, medium voltage is supplied to a ramp, as the ramp 15, only when the track relay, as the track relay 7, of the corresponding block is deenergized; and when such conditions exist, the vehicle approaching the ramp 15 will have had its train controlling mechanism 70 set into operation at the ramp 14 next in the rear. If the relay 67 were energized when the shoe 56 engages a ramp between which and the rail a medium difference of potential existed the relay 66 would be energized because impedance 76 under such a condition would be shunted because of the fact that relay 67 was energized, consequently the medium difference of potential would be sufficient to so energize relay 66 that its armatures would be raised and consequently relay 67 would be maintained energized and the train would proceed uninfluenced by device 70, but this condition could only occur due to an irregularity. If relay 67 were deenergized when the train encountered a ramp between which and a rail a medium difference of potential existed, then relay 66 would not be energized because it would then have impedance 76 in series with it, consequently the train would have to proceed under control of 70.

The greater portion of the ramps, as, 14, 15 and 16, is placed ahead of the insulating joints 8, because it requires a longer interval of time to deenergize the relays on the car than it takes to energize them. In the previous description will be found cases where the contact of a shoe with a ramp causes an energization of some of the relays followed by a deenergization before the shoe has left the ramp and because of the presence of the shoe on the ramp.

Although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention.

What I claim as new and desire to secure by Letters Patent of the United States, is:

1. In an automatic train control system, in combination: a trackway divided into track circuit sections and having a movable vehicle thereon; a movable contact member positioned on the movable vehicle; means governed by the track circuit sections for creating a high, medium or low difference of potential between the ramp and a rail of the trackway; a partial circuit on said vehicle including an impedance and a relay; means for closing said partial circuit by the contact of the contact member with the ramp and energizing said relay and causing it to lift its armature when a high difference of potential exists between the ramp and a rail of

the track; a second relay; means governed by said first relay for energizing said second relay; means including a circuit controller governed by said movable contact member 5 for maintaining said second relay energized; means governed by said second relay for forming a shunt path about said impedance whereby the medium difference of potential between the ramp and a rail will when the 10 contact member contacts a ramp energize the first mentioned relay sufficiently to cause it to raise its armature; means governed by the second mentioned relay for controlling the movable vehicle; and means for governing the vehicle controlled by the low difference of potential.

2. In an automatic train control system, in combination: a trackway divided into track circuit sections each including a translating device; ramps positioned at the entrance to each track circuit section; means for creating a difference of electrical potential of high, medium or low value; means governed by the translating device of a section 25 at the entrance to which a ramp is positioned to create a high difference of potential between that ramp and a rail of the trackway; means governed by the translating device of the section at the entrance to which a ramp is positioned and the translating device of the track circuit section in 30 advance to create a medium or low difference of potential between that ramp and a rail of the track; and means responsive selectively to said differences of potential for controlling a movable vehicle.

3. In an automatic train control system, in combination: a vehicle; brake controlling means for controlling the movement of said vehicle and set into operation when deenergized; a circuit for normally energizing said brake controlling means; a relay for controlling said circuit; a circuit controller for governing said relay; a circuit for maintaining said means energized independently 45 of the operation of said relay; and means for simultaneously governing said last mentioned circuit and said circuit controller.

4. In an automatic train control system, in combination: a track; a vehicle adapted to travel over said track and having brakes for retarding its movement; mechanism for controlling the brakes of said vehicle, said mechanism being set into operation when deenergized; a relay for normally maintaining said mechanism energized; a normally closed circuit for energizing said relay; contact rails located at intervals along said trackway; a contact shoe carried by 55 said vehicle and arranged to cooperate with said contact rails; a circuit controller operated by said contact shoe and opened when said shoe is operated by engagement with one of said contact rails, said circuit con-

troller being included in said normally closed circuit; a normally closed circuit for maintaining said mechanism energized independently of the operation of said relay; and means governed by said contact shoe for opening said last mentioned circuit when 60 said shoe engages one of said contact rails.

5. In an automatic train control system, in combination: a track; a vehicle adapted to travel over said track; mechanism for governing the movement of said vehicle; a circuit for governing said mechanism; a circuit controller included in said circuit; a relay for controlling said circuit controller; a normally closed circuit for energizing said relay; a circuit controlling device carried by 75 said vehicle for interrupting said normally closed circuit; traffic controlled means located at intervals along said track for operating said circuit controlling device; another relay for controlling said circuit controller; and means controlled by said last mentioned means for energizing said another relay. *

6. In an automatic train control system, the combination with a vehicle and a track 80 therefor, of impulse transmitting devices located at intervals along the track and adapted to assume different controlling conditions, one or more of said devices being capable of assuming an additional distinctive controlling condition, means for automatically governing the controlling conditions of all of said devices in accordance 85 with traffic conditions in advance, manually controlled means for causing the distinctive controlling condition of the particular devices, automatic train control apparatus on the vehicle governed by the controlling conditions of said devices and adapted to gradually regulate the progress 90 of the vehicle, and separate automatic train control mechanism on the vehicle governed by the distinctive controlling condition of the particular devices and adapted to immediately arrest the movement of the vehicle.

7. In a system for protecting railway traffic, in combination: a railroad track; a vehicle adapted to travel over said track; separate traffic protecting apparatus and mechanism having operating conditions corresponding to the occasions where the vehicle should proceed cautiously or should stop, respectively; means on the vehicle for controlling said apparatus and responsive to different voltages; other means for controlling said mechanism which operates to set the mechanism into operation when no voltage is applied to it; devices carried by the vehicle and located at intervals along the track in cooperative relation for applying different voltages to said first mentioned means in accordance with the traffic conditions along the track; and manually con-

trolled means for controlling said devices to cut off the supply of voltage to said second mentioned other means.

8. In a system for protecting railway traffic, in combination: a railroad track; a vehicle adapted to travel over said track; separate traffic protecting apparatus and mechanism having operating conditions corresponding to the occasions where the vehicle should proceed cautiously or should stop, respectively; said mechanism and said apparatus both having a tendency to assume their active condition; means energized by a source of current carried by the vehicle for maintaining said mechanism and said apparatus in their inactive condition; other means selectively responsive to potential differences of different intensities for maintaining said apparatus and said mechanism in their inactive condition; and means for energizing said last mentioned means by a current distinctive in character from the current derived from said source and for simultaneously rendering said first mentioned means ineffective.

9. In a system for protecting railway traffic, in combination: a track divided into track circuit sections; a contact rail associated with each track section; partial circuits associated with each contact rail and terminating at that contact rail and a track rail of the track; means controlled by each track circuit section for energizing said corresponding partial circuits with currents of different intensities according to whether or not the corresponding track circuit section is occupied; and manually controlled means associated with a contact rail for interrupting all of the partial circuits associated therewith.

10. In a system for protecting railway traffic, in combination: a vehicle; traffic protecting apparatus carried by the vehicle; two relays carried by the vehicle for controlling said apparatus; said relays being connected in parallel; means included in the circuit for one of said relays for increasing the opposition to the flow of current therein; a shunt for said means; and means for closing said shunt when the other relay is deenergized.

11. In an automatic train control system, the combination with a vehicle and a track therefor divided into blocks, of an impulse transmitting device associated with each block and adapted to assume different controlling conditions, sources of electrical energy of different characteristics for producing the different controlling conditions of said devices, circuits for controlling the connection between said sources and each device, traffic controlled means for governing said circuits, and manually controlled means for disconnecting one or more particular

impulse transmitting devices from their respective sources.

12. In an automatic train control system, the combination with a railway track, of an impulse device associated therewith and adapted to assume different controlling conditions, circuits for supplying electrical energy of different characteristics to said impulse device to produce the different controlling conditions thereof, traffic controlled means for governing said circuits automatically, said circuits regardless of traffic conditions normally supplying some energy to the impulse device, and manually controlled means for interrupting all of said circuits and thereby deprive said impulse device of all electrical energy.

13. In an automatic train control system, the combination with a vehicle and a track therefor, of separate automatic traffic protecting apparatus and automatic train control mechanism on the vehicle for governing the movement thereof according to whether the vehicle should proceed cautiously or stop respectively, said apparatus being responsive to variations in the amount of current supplied thereto, said mechanism being rendered effective by the failure to supply current thereto, impulse transmitting means comprising elements partly on the vehicle and partly along the track for governing the amount of current supplied to said apparatus and mechanism in accordance with traffic conditions, and manually controlled means for cutting off all supply of current to said apparatus and mechanism at predetermined control points along the track.

14. In an automatic train control system, the combination with a track divided into blocks each having a track relay, of a ramp located adjacent to the entrance end of each block, a partial circuit for each ramp including a high voltage source of current and the front point of the track relay of the corresponding block, a second partial circuit for each ramp including a medium source of current, a back point of the track relay of the corresponding block and the front point of the track relay of the next block in advance of the corresponding block, and a third partial circuit for each ramp including a low voltage source of current, the back point of the track relay of the corresponding block; and the back point of the track relay of the block next in advance of the corresponding block.

15. In an automatic train control system, the combination with a track divided into blocks each having a track circuit, of an impulse device associated with each block, partial circuits for each impulse device including sources of current of different voltages and controlled by the track circuit of

the block next in advance of the corresponding block, another partial circuit controlled solely by the track circuit of the corresponding block, and means controlled by the track circuit of each block for alternately connecting the corresponding ramp to the first mentioned partial circuits and said another partial circuit.

16. In an automatic train control system, the combination with a track divided into blocks, of an impulse device associated with each block, a circuit for controlling each impulse device, means responsive to the presence of a train in the corresponding block for controlling said circuit, two other circuits for controlling each impulse device having sources of current of different voltages included therein, means responsive to the presence of a train in the block next in advance of the corresponding block for governing said other circuits, and means governed by the progress of a train past an impulse device for alternately connecting said first mentioned circuit and said other circuits to the corresponding impulse device.

17. In an automatic train control system, the combination with a vehicle and a track therefor, of apparatus on the vehicle for regulating its progress along the track, separate mechanism for immediately arresting the movement of the vehicle, impulse transmitting means along the track and controlled in accordance with traffic conditions for governing said apparatus, and manually controlled means associated with one or more of the impulse transmitting means for governing said mechanism.

18. In an automatic train control system, the combination with a vehicle and a track therefor, of means on the vehicle for regulating the speed thereof from point to point along the track, traffic controlled impulse devices at said points for governing said means, one or more particular impulse devices being capable of assuming an additional distinctive controlling condition, and means on the vehicle governed by the distinctive controlling condition of said particular impulse devices for immediately arresting the movement of the vehicle independently of the first mentioned means.

19. In an automatic train control system for railroads, in combination: a railroad track divided into blocks; a vehicle adapted to travel over said track; an impulse device at the entrance to each block adapted to transmit controlling impulses to a passing vehicle both prior and subsequent to its entrance into that block; control circuits and sources of current associated with each impulse device and controlled by the track relays of the corresponding block and the next block in advance, said control circuits caus-

ing an impulse device to be energized by the current of one characteristic when the corresponding block is not occupied, to be energized by current of another characteristic when said corresponding block is occupied and the next block in advance is not occupied, and to be deenergized when both of said blocks are occupied; and train control apparatus on the vehicle selectively responsive to the different energized and deenergized conditions of said impulse devices.

20. In an automatic train control system for railroads, in combination: a railroad track divided into blocks; a vehicle adapted to travel over said track; automatic traffic protecting apparatus on the vehicle; control means for governing said apparatus which is selectively responsive in different ways to currents of two different characteristics dependent upon whether or not said apparatus is then active or inactive; and means for supplying current from the track to said controlling means at the entrance to each block, the characteristic of such current supplied by said means being automatically controlled in accordance with the presence or absence of a vehicle in the corresponding block.

21. In an automatic train control system for railroads, in combination: a railroad track divided into blocks; a vehicle adapted to travel over said track; an impulse device associated with each block; two sources of current on the track of different voltage for each impulse device; circuits including said sources for energizing each impulse device, one circuit being normally closed; and means for shifting the control of each impulse device from said normally closed circuit to the other circuit as the vehicle passes the corresponding impulse device.

22. In an automatic train control system for railroads, in combination: a vehicle; mechanism for controlling the movement of the vehicle; a normally energized relay for governing said mechanism; a normally deenergized relay for governing said first mentioned relay; a circuit including said normally deenergized relay; and means for increasing the opposition to the flow of current in said circuit without actually interrupting it upon deenergization of said first mentioned normally energized relay.

23. In an automatic train control system for railroads, in combination: a track divided into blocks having track relays; a vehicle adapted to travel over said track; traffic protecting mechanism on the vehicle responsive to electric currents of different characteristics; an impulse device at the entrance to each block; two circuits for controlling each impulse device and including sources of current of different electrical characteristics; and means controlled by the

- track relay of the corresponding block for closing a break in one circuit when said block is not occupied and for closing a break in the other circuit when said block is occupied.
24. In a system for protecting railway traffic, in combination: a vehicle; automatic traffic protecting apparatus carried by said vehicle; a relay for controlling said apparatus; a second relay responsive to alternating current for governing the first relay; a contact shoe carried by said vehicle; two partial circuits of different impedance for governing said second relay and terminating at said contact shoe and at the wheels of said vehicle; and means governed by said first relay for selectively controlling said partial circuits.
25. In a system for protecting railway traffic, in combination: a track divided into track circuit sections; a contact rail associated with each track section; two partial circuits associated with each contact rail for establishing differences of potential of different intensities between that contact rail and a track rail, said partial circuits being selectively controlled by the corresponding track section according to whether or not that track circuit section is occupied, one of said partial circuits being also controlled by the next track circuit section in advance and being closed only when that next track section is unoccupied.
26. In a system for protecting railway traffic, in combination: track rails constituting a railroad track, said track being divided by insulating joints into track sections; a source of current and a relay associated with each of said sections and constituting a normally closed track circuit; contact rails associated with said track circuit sections and extending along said track on both sides of the insulating joint at the entrance to the corresponding track circuit section; a vehicle adapted to travel on said track; a contact shoe carried by said vehicle and arranged to engage said contact rails; and automatic traffic protecting apparatus on said vehicle governed by the cooperation of said contact shoes and said contact rails.
27. In an automatic train control system, a partial circuit on a vehicle, a relay included in said partial circuit, means controlled by said relay for modifying the electrical characteristics of the partial circuit and thereby rendering the energization of the relay dependent upon the characteristics of the electrical energy supplied to said partial circuit in accordance with the existing condition of the relay and means responsive to traffic conditions along the track for supplying electrical energy of different characteristics to the partial circuit in accordance with said traffic conditions.
28. In an automatic train control system, a partial circuit on a vehicle, an electro-responsive device included in said circuit, means controlled by said device for varying the opposition to the flow of current in said partial circuit, and traffic controlled means along the track for supplying different voltages to the partial circuit on the vehicle in accordance with traffic conditions ahead.
29. In an automatic train control system, in combination: a track divided into blocks each having a track relay; an impulse device located near the entrance end of each block and disposed in position to cooperate with an impulse device on a passing vehicle both prior and subsequent to the entrance of that vehicle into the corresponding block, said impulse devices along the track being adapted to have different controlling conditions; a circuit controlled by the track relay of the block immediately in advance of an impulse device for determining the occurrence of one controlling condition thereof; and a second circuit controlled by the track relay of the second block in advance of the impulse device for determining the occurrence of another controlling condition of said impulse device.
30. In an automatic train control system, in combination: a track divided into blocks each having a track relay; a contact rail located near the entrance end of each block; a partial circuit associated with each contact rail and including the front point of the track relay of the corresponding block, said partial circuit including a source of current; and a second partial circuit associated with each contact rail and including the back point of the track relay of the corresponding block and a front point of the track relay of the next block in advance, said second partial circuit including a source of current of lower voltage than the first mentioned source.
31. In an automatic train control system for railroads having tracks divided into blocks each provided with a track relay, in combination: an impulse device at the entrance to each block arranged to transmit impulses to a passing vehicle both prior and subsequent to its entrance into that block; a control circuit for energizing each impulse device including a source of high voltage and governed by the track relay of the corresponding block; a second control circuit for energizing each impulse device including a source of low voltage and having its continuity governed by the track relays of the corresponding block and the next block in advance; automatic train control apparatus on the vehicle adapted to be influenced distinctively by the different energized or deenergized conditions of each impulse device, said apparatus being restored to its inactive condition by the influence of an impulse device.

- vice supplied with high voltage; being maintained but not restored by the influence of a device supplied with low voltage, and being set into operation by a deenergized impulse device.
32. In an automatic train control system, in combination: a track divided into blocks; an impulse device located near the entrance end of each block; two controlling circuits for each impulse device having sources of current included therein which have different voltages, one of the controlling circuits being closed when the corresponding block is not occupied, and the other controlling circuit being closed when the corresponding block is occupied and the next block in advance is not occupied.
33. In an automatic train control system, in combination: a track divided into blocks, an impulse device associated with each block; two controlling circuits for governing the controlling condition of each impulse device; the continuity of one controlling circuit being interrupted when the block corresponding to the associated impulse device is occupied, the continuity of the other controlling circuit being interrupted when the block next in advance of the block corresponding to the associated impulse device is occupied; and means associated with each block and responsive to the presence of a train thereon for selectively controlling the connection between the corresponding impulse device and its controlling circuits.
34. In an automatic train control system, in combination: a track divided into blocks; an impulse device associated with each block; two controlling circuits for each impulse device having their continuity dependent upon the presence or absence of a train in the corresponding block and the next block in advance respectively; and means governed by a passing train for rendering the controlling circuits for an impulse device successively effective to determine the controlling condition of that impulse device.
35. In an automatic train control system, in combination: a track divided into blocks; means comprising cooperating elements partly on the vehicle and partly along the track for transmitting controlling impulses to the vehicle as it reaches the entrance to each block, said elements along the track being capable of assuming different controlling conditions; means for rendering one controlling condition of the trackway elements dependent upon the presence or absence of a train in the corresponding block; and means for rendering another controlling condition of the trackway elements dependent upon the presence or absence of a train in the block next in advance of the corresponding block, said means being automatically rendered effective in succession during the passage of the vehicle.
36. In an automatic train control system comprising automatic train control apparatus carried by a railway vehicle and having an active and an inactive condition, impulse devices at intervals along the track responsive to the presence of a train on the track and having different controlling conditions corresponding to the extent of unoccupied track in advance thereof, and means on the vehicle cooperating with said impulse devices and acting to render said train control apparatus active or inactive dependent upon its then existing active or inactive condition and upon the controlling condition of said impulse devices.
37. In an automatic train control system, in combination: a track divided into blocks each having a track relay; an impulse device at the entrance to each block and arranged to transmit impulses to a passing vehicle both prior and subsequent to its entrance into that block; a circuit for energizing each impulse device by current of one characteristic and including a front contact of the track relay of the corresponding block; and a second circuit for energizing each impulse device by current of another characteristic and including a back contact of the track relay of the corresponding block and a front contact of the track relay of the block next in advance.
38. In an automatic train control system for railroads having tracks divided into blocks each having a track relay, in combination: an impulse device at the entrance to each block arranged to transmit impulses to a passing vehicle both prior and subsequent to its entrance into that block; trackway circuits and sources of current for placing each impulse device in one controlling condition when the corresponding block is not occupied, in a second controlling condition when the corresponding block is occupied and the next block in advance is not occupied, and a third controlling condition when both of said blocks are occupied; and automatic train control apparatus on the vehicle responsive to the different controlling conditions of said impulse devices and adapted to be restored to its inactive condition by the first controlling condition, maintained but not restored by the second, and set into operation by the third.
39. In an automatic train control system for railroads having tracks divided into blocks each having a track relay, in combination: automatic train control apparatus on a vehicle adapted under the influence of an impulse of a predetermined character to remain in the same active or inactive condition then existing; and trackway circuits and impulse transmitting devices including means for transmitting to the vehicle such impulse of predetermined character at the entrance to each block when the next block

in advance is not occupied, together with means for causing said train control apparatus to be restored to its inactive condition at the entrance to each unoccupied block, these means acting in succession to influence the apparatus on a passing vehicle as it enters each block.

40. In an automatic train control system for railroads having tracks divided into 10 blocks, in combination: train control apparatus on a vehicle included in a normally closed circuit and inactive when energized; controlling means responsive to currents of different voltages for governing said normally closed circuit; and means for establishing communication between the vehicle and the track at the entrance to each block and adapted to supply currents of different voltages to said control means successively 15 as the vehicle passes each impulse device de- 20

pendent upon traffic conditions in that block and the block next in advance, whereby said train control apparatus will be restored at the entrance to each unoccupied block and will be set into operation or maintained 25 inactive respectively depending upon the presence or absence of a train in the next block in advance.

41. In combination, a railway track, a vehicle thereon, ramps on said track energized by a source of alternating current, a shoe on said vehicle engaging said ramps, a closed circuit energized by direct current on said vehicle and interrupted by said shoe, an alternating current relay responding to 30 the current in said ramps, said relay when energized, closing the circuit interrupted by 35 said shoe.

WINTHROP K. HOWE.
